UNITED STATES PATENT OFFICE.

LOREN L. WHITNEY, OF HAMMOND, INDIANA, ASSIGNOR TO AMERICAN STEEL FOUNDRIES, OF CHICAGO, ILLINOIS, A CORPORATION OF NEW JERSEY.

Brake Beam and Method of Making Same.

Application filed January 10, 1923. Serial No. 611,726.

To all whom it may concern:

Be it known that I, LOREN L. WHITNEY, a citizen of the United States, residing at Hammond, in the county of Lake and State of Indiana, have invented certain new and useful Improvements in Brake Beams and Methods of Making Same, of which the following is a specification.

This invention relates to a brake beam and method of making same.

One object of the invention is to provide a simple and efficient method of making a truss type of brake beam.

Another object is to provide a truss type of brake beam which is simple and durable in construction and in which the parts are made rigid and cooperate in an improved manner to meet the various requirements for successful commercial use.

These and other objects are accomplished by means of the arrangement and method disclosed on the accompanying sheets of drawings, in which—

Figures 1, 2 and 3 are, respectively, a rear elevation, top plan view, and end elevation of a channel shaped blank for the compression member of the brake beam;

Figures 4, 5 and 6, respectively, are similar views showing said blank with the camber bent therein;

Figures 7 and 8 are top and side elevations of the strut forming a part of the truss type of brake beam;

Figures 9 and 10, are, respectively, a rear elevation and top plan view showing the strut applied to the compression member;

Figure 11 is an end view of the end of the compression member before further treatment;

Figures 12 and 13 are, respectively, a rear elevation and top plan view of the strut and compression member showing the outer ends of the flanges of the compression member expanded to form enlarged tension rod seats;

Figure 14 is an end view of the end of the compression member shown in Figures 12 and 13;

Figures 15 and 16 are, respectively, a top plan view and an end view of the tension member blank;

Figure 17 is a top plan view of the tension member after it is given its V shape intermediate its ends;

Figures 18 and 19 are, respectively, rear

elevation and top plan views of the three main parts of the brake beam showing the intermediate portion of the tension member applied to the strut and the end portions seated within the expanded end portions of the channel shaped compression member;

Figure 20 is an end view of the end portions of the tension and compression members showing the former seated in the latter;

Figures 21 and 22 are rear elevation and top plan views, respectively, of the same brake beam parts after the expanded flanged portions of the compression member are wrapped around or embrace the ends of the tension member;

Figure 23 is an end view of the end portions of the tension and compression members showing the end of the tension member completely embraced by the compression member;

Figures 24, 25 and 26 among other things, show ends of the tension and compression members after the first forging operation in which the end portions of said tension and compression members are upset, collar portions being formed on both the tension and compression members;

Figures 27, 28 and 29 are similar views after the second forging operation showing the ends of the tension and compression members further upset and the collars thereon more perfectly formed; and

Figures 30, 31 and 32 are similar views, respectively, after the third forging operation in which the trunnions for brake heads are completely formed and the collars on the tension member within the collars of the compression member are formed for rigidly holding said tension and compression members together.

The various novel features of the invention will be apparent from the following description and drawings and will be particularly pointed out in the appended claims.

Referring to the figures of the drawings, it will be noted that the compression member is formed from the blank 40 channel shaped in section, having a web 41 and flanges 42. The blank is first provided with a camber as shown at 43.

A strut 44 having a banded portion 45 is then applied over the compression member so that the latter is embraced by the banded portion 45. Then the ends of the compression member are treated in a manner to form

rounded seat portions 46 for the tension member and also to expand laterally the ends of the compression member flanges 42 to form enlarged embracing portions 47, 5 which, as will be pointed out later, embrace the ends of the tension member.

The tension member blank 48 is then provided and given V shape intermediate its ends, as shown in Figures 15, 16 and 17, the 10 tension member in this instance being circular in section. The intermediate portion of the tension member 48 is then applied to the strut and the ends 49 of the tension member seated within the rounded seat portions 46 15 of the compression member, whereupon the expanded portions 47 of the compression member are wrapped around to completely embrace the ends of the tension member, as shown in Figures 21, 22 and 23.

20 The ends of the tension and compression members are then heated and given their first forging operation, in which the ends of the tension and compression members are both upset, as shown in Figures 24, 25 and 25 26, shoulders 50 and 51 being started, as shown in said figures. The ends of the tension and compression members are then given the second forging treatment in which they are further upset as shown in Figures 27, 30 28 and 29. In this connection it will be noted that the shoulders 50 and 51 on tension and compression members, respectively, are substantially completely formed, the shoulder 50 being within the shoulder 51.

35 Then the tension and compression members are given their third forging operation in which the ends of the tension and compression members are further upset and additional collars 52 and 53 formed on tension and compression members, respectively, the collar 52 being located within the collar 53. The cooperating collars 50, 51, 52 and 53 rigidly hold the tension and compression members together. In this way, 45 also, the ends of the brake beam are provided with trunnions for brake heads, said trunnions having an intermediate groove 54 for the reception of a locking block to prevent accidental lateral movement of an associated brake head.

50 By means of this method, a truss type of brake beam is provided which is adapted to meet the various requirements for successful commercial use, the method being simple, efficient and practicable.

55 It is my intention to cover all modifications of the invention falling within the spirit and scope of the following claims.

I claim:

60 1. The method of making a truss type of

brake beam consisting first in providing a channel shaped compression member blank, then connecting the strut thereto, then expanding the ends of the flanges of said blank, then applying the tension member to said strut and compression member so that the ends of the tension member are embraced by the expanded flanges, and then upsetting and forming shoulders on the embracing portions of said tension and compression members to firmly connect same and form 70 brake head trunnions.

2. The method of making a truss type of brake beam consisting first in providing a channel shaped compression member blank, 75 then connecting the strut thereto, then expanding the ends of the flanges of said blank, then applying the tension member to said strut and placing the ends of said tension member between the expanded flanges, then bending said expanded flanges around the ends of said tension member, and then upsetting and forming shoulders the embracing portions of said tension and compression members to firmly connect same and form 80 85 brake head trunnions.

3. The method of securing together the ends of the tension and compression members of a truss type of brake beam consisting in expanding the end portions of the compression member, then folding said expanded ends around the tension member, and then forging shoulders on the ends of said tension and compression members to firmly connect same and form 90 95 brake head trunnions.

4. The method of securing together the ends of the tension and compression members of a truss type of brake beam consisting in folding one of said members around the other and then forging shoulders on the ends of said tension and compression members to firmly connect same and form 100 105 brake head trunnions.

5. A brake beam including tension and compression members connected at their outer ends, shoulders being formed on said tension and compression members cooperating to firmly hold together said members.

6. A brake beam including tension and compression members connected at their outer ends, said tension member having shoulder portions, and said compression member also having shoulder portions embracing the shoulder portions on said tension member for cooperating to securely hold together said tension and compression members.

Signed at Hammond, Indiana, this 5th day of January, 1923.

LOREN L. WHITNEY.
